US00D761787S

(12) **United States Design Patent**
Yamazaki

(10) **Patent No.:** US D761,787 S
(45) **Date of Patent:** ** *Jul. 19, 2016

(54) **PORTABLE INFORMATION TERMINAL**

(71) **Applicant:** SEMICONDUCTOR ENERGY
LABORATORY CO., LTD., Atsugi-shi,
Kanagawa-ken (JP)

(72) **Inventor:** Shunpei Yamazaki, Tokyo (JP)

(73) **Assignee:** Semiconductor Energy Laboratory
Co., LTD., Kanagawa-ken (JP)

(*) **Notice:** This patent is subject to a terminal disclaimer.

(**) **Term:** 14 Years

(21) **Appl. No.:** 29/498,841

(22) **Filed:** Aug. 8, 2014

(30) **Foreign Application Priority Data**

Feb. 13, 2014 (JP) 2014-002830

(51) **LOC (10) Cl.** 14-02

(57) **CLAIM**

I claim, the ornamental design for a portable information terminal, as shown and described.

DESCRIPTION

FIG. 1 is a front view of a portable information terminal showing my new design;

FIG. 2 is a rear view;

FIG. 3 is a right side view;

FIG. 4 is a left side view;

FIG. 5 is a top view;

FIG. 6 is a bottom view;

FIG. 7 is a front view in which a flexible display is unfolded;

FIG. 8 is a rear view in which the flexible display is unfolded;

FIG. 9 is a right side view in which the flexible display is unfolded;

FIG. 10 is a left side view in which the flexible display is unfolded;

FIG. 11 is a top view in which the flexible display is unfolded;

FIG. 12 is a bottom view in which the flexible display is unfolded; and,

FIG. 13 is an enlarged sectional view taken from A-A' in FIG. 1 with the internal mechanisms omitted.

The portable information terminal is used in a state in which the flexible display is folded, unfolded or curved as necessary.

1 Claim, 7 Drawing Sheets
